UNITED STATES PATENT OFFICE.

CHARLES H. STULL, OF SEATTLE, WASHINGTON.

ELECTRIC-LIGHT SUPPORT.

1,366,682.

Specification of Letters Patent. Patented Jan. 25, 1921.

Application filed November 14, 1918. Serial No. 262,471.

To all whom it may concern:

Be it known that I, CHARLES H. STULL, a citizen of the United States, residing at Seattle, in the county of King and State of Washington, have invented Electric-Light Supports, of which the following is a specification.

My invention relates to the mounting of an electric incandescent lamp and its shade or reflector in a way to absorb the shocks and vibrations to which the lamp is subjected in machine shops and other places and which tend to break the delicate filament. I also provide for the adjustment of the lamp within its reflector to bring it into focus.

Figure 1, is a view in perspective of a construction embodying my invention;

Fig. 2, is a view of my invention in elevation applied to a two-piece lamp receptacle.

Fig. 3, is a view of my invention applied to a mogul lamp socket.

Fig. 4, is in part a longitudinal sectional view of my invention applied to a reflector.

Fig. 5, is a view of a modified form of my invention.

The band 6 is adapted by means of the screw 7 to be clamped about the lamp socket part 8, (that is the part containing the lamp grip) of a porcelain lamp socket or receptacle and thus serve as a lamp socket holding means. (While "socket" and "receptacle" as sometimes used signify different parts, herein they are used synonymously.) Resilient wires, preferably four in number, 9, 10, 11 and 12, all of which are similar in construction and preferably provided with a coil 13 are fixedly secured to said band 6 at one extremity and fixedly secured to a base piece 14 at the other. This base piece 14 is secured to the threaded flange part 15 of any standard reflector which reflector 16 is held in place against said part 15 by a bushing 17, which in turn is held in place by nut 18. The threaded portion 19 of the part 15 adapts the same to be held in the conduit 20 of any standard or wall bracket.

In Fig. 5 a modified form is illustrated wherein a single wire resilient means 21 is employed. By soldering certain of the coils 50 alternately as at 22 this single member wire spring can be made to contain within itself oppositely directed forces which will operate to produce a steady illumination.

The operation of my invention is as follows:—

The band 6 is clamped about a lamp socket or receptacle part 8, that is the part containing the lamp grip. The resiliency of the wires 9, 10, 11 and 12 serves to take up and neutralize severe shocks and jars that may be transmitted through the supporting standard or bracket to the lamp. These wires are caused preferably to exert a laterally directed thrust relative to the band or holding means 6, so that the oppositely disposed resilient members operate against each other and in this way effect the very important result of producing a very steady light without sacrificing the advantages of their resiliency. The great importance of this appears when it is remembered that the use of riveting hammers and other pneumatic devices for instance, produce a constant vibration and jar of the entire surrounding supports, and it is at the same time imperative that good illumination be available on account of the requisite fineness or accuracy necessary in connection with such work. This applies also to such operators of acetylene burners who may be engaged at work on adjoining parts. Such operators, often in obscure positions, must follow precisely the prescribed markings for their cuttings in order to make proper fittings of required nicety. The great steadiness of light made possible under such conditions by my invention increases greatly the ordinary working efficiency of the high-priced, skilled operators engaged in such construction.

When said shock absorber is to be employed in conjunction with a reflector, it is manifest that the socket can be adjusted to utilize practically the full reflecting powers of the reflector in one of two ways; first, the holding means 6 may be clamped near the edge 23 or the edge 24, and again the length of wires 9, 10, 11, and 12 may be made shorter or longer as the case requires. Furthermore, the design of lamp bulb, *i. e.*, 100 whether a standard or stereopticon design of bulb, will affect the degree of utilization of the reflective power of the reflector. In one or the other of these ways, it is manifest that the lamp may be placed to the best advantage 105 relative the focal powers of the reflector. The reflector also serves in addition to local-

izing the light, as a protection against rain and weather.

It is preferred to construct the resilient means in the form of wires rigidly fixed to the base, because such construction permits the wires to be so adjusted as to support the lamp at any desired angle.

Obviously, changes may be made in the forms, dimensions and arrangements of the parts of my invention without departing from the principle thereof, the above setting forth only a preferred form of embodiment. For example, although I prefer the use of a plurality of resilient wires, manifestly many of the advantages of my invention may be secured by a single resilient wire supporter made of very stiff or tightly coiled wire.

I claim:

1. A holder for an incandescent lamp com-

prising a reflector-supporting base provided on its outer side with attachment devices for the external support, a socket-clamp adapted to grip the outside of the lamp socket and resilient supporting means interposed between said clamp and the inner side of the aforesaid base.

2. A holder for an incandescent lamp comprising a reflector-supporting base provided on its outer side with attachment devices for the external support, a socket-clamp adapted to grip the outside of the lamp socket at different points thereon, and resilient supporting wires connecting said clamp and the said supporting-base.

In witness whereof, I hereunto subscribe my name this 1st day of Nov., A. D., 1918.

CHARLES H. STULL.
